F. H. LANGMUIR

TRUNK LOCK

Filed June 21, 1923

UNITED STATES PATENT OFFICE.

FRANK H. LANGMUIR, OF RACINE, WISCONSIN, ASSIGNOR TO HARTMANN TRUNK COMPANY, OF RACINE, WISCONSIN, A CORPORATION OF WISCONSIN.

TRUNK LOCK.

Application filed June 21, 1923. Serial No. 646,861.

This invention relates to improvements in automatic trunk locks, more particularly adapted for wardrobe trunks.

It is one of the objects of the present invention to provide an automatic trunk lock for locking trunks of the wardrobe type in which the trunk is divided medially vertically to form a drawer section and a wardrobe section. The two sections are adapted to be swung together to closed position and one of the sections is provided with an open top having a top cover.

A further object of the invention is to provide a trunk lock for locking the two sections together, which is automatically controlled by the movement of the top cover to closed position.

A further object of the invention is to provide an automatic trunk lock which is normally in unlocked position and which is moved to a locked position when another portion of the trunk controlled by an associated lock is moved to closed position.

A further object of the present invention is to provide an automatic trunk lock which will draw the two sections of the trunk tightly together when the top cover is moved to closed position.

A further object of the invention is to provide an automatic trunk lock which is of simple construction, is strong and durable and is well adapted to withstand the hard knocks incident to transportation.

With the above and other objects in view, the invention consists of the improved automatic trunk lock and its parts and combinations as set forth in the claims, and all equivalents thereof.

In the accompanying drawing, in which the same reference characters indicate the same parts in all of the views:

Fig. 1 is a front view of a wardrobe trunk provided with the improved automatic lock, the trunk sections being shown in open position;

Fig. 2 is an inside detail view of trunk portions on a larger scale with the automatic lock mounted thereon and shown in open position;

Fig. 3 is a similar view of the lower portion of the trunk showing the lower lock in locked position;

Fig. 4 is a vertical sectional view taken on line 4-4 of Fig. 2; and

Fig. 5 is a detail side view of one of the

locking members and associated parts removed from the lock.

Referring to the drawing, the numeral 8 indicates a trunk body which is divided vertically to form a drawer section 9, and a wardrobe section 10 which is open at its upper end and is provided with a top cover 11. The top cover 11 is provided with an ordinary automatic hasp lock 12 positioned to engage an escutcheon plate 13 mounted on the upper portion of the drawer section 9 and is the only outer keyed lock carried by the trunk. The wardrobe section of the trunk is locked to the drawer section by a pair of automatic locks 14 mounted respectively on the upper and lower side portions of the trunk. Each automatic lock comprises a hook-shaped member 15 mounted on a pivot pin 16 between the lock plate 17 and the outer side of the wardrobe section 10. Said member 15 is formed with a wedging edge 15' adapted to engage a shoulder or its equivalent an antifriction roller 18 mounted within the escutcheon plate 19 to initially draw the two sections of the trunk together before the recessed portion 20 engages the roller to lock the two sections together. The member 15 is also formed with an elongated opening 21 through which extends an actuating pin 22 mounted on a vertical reciprocal actuating bar 23 which is positioned within the trunk section 10 and is guided by strap guides 24. The side portion of the trunk section is provided with an elongated opening 25 to accommodate the pin 22 and to permit the vertical reciprocations thereof, and the portion of the pin within said opening carries an antifriction roller 26 to reduce friction.

The escutcheon plates 19 and rollers 18 are firmly mounted on the drawer section of the trunk so that when the wedging edges of the hook members initially engage the rollers, the drawer section of the trunk will be drawn into close engagement with the wardrobe section and the said hook members will then hold the parts locked together.

The lower end of the actuating bar 23 is reduced and forms a shoulder 27 and a coiled spring 28 surrounding the reduced portion 105 bears against the shoulder. A bracket member 29 having an upwardly extending reduced portion forming a shoulder 30 is mounted on the inner side of the wardrobe section beneath the lower end of the bar 23 110

and receives the lower end of the spring 28, said spring normally holding the rod in its upper position and the hook members in unlocked position, as shown in Fig. 2.

5 The upper end portion 23' of the bar is angled inwardly and extends above the upper edge of the wardrobe section so that when the sections are swung together and the top cover 11 is swung to closed position, a 10 plate 31 mounted on the top cover will engage said upper end 23' and force the bar 23 downwardly and the hook members to locked position. In moving to locked position the hook members will engage the 15 rollers of the escutcheon plates and draw the two sections closely together.

From the foregoing description, it will be seen that the automatic trunk lock is of very simple construction and is well 20 adapted for the purpose described.

What I claim as my invention is:

1. An automatic locking means for a trunk having three hinged together elements, comprising an escutcheon plate carried on 25 the outer side of one of the elements, a hook like member carried on the outer side of a second element and having a locking recess and a wedging edge engageable with the escutcheon plate when the two elements are 30 adjacent each other, a third element, and means engaged by the third element in moving to closed position for causing the hook like member to draw the first and second elements together and then lock them in 35 closed position.

2. An automatic locking means for a trunk having three hinged together elements, comprising an escutcheon plate having a shoulder, a hook-like pivoted member having a wedging edge which engages the shoulder to draw two of the elements together and also having a recessed portion for lockingly engaging the shoulder, a bar engaged by the third element and having a pin and 45 slot engagement with the hook like member for moving the hook-like member to locking position, and a spring means for normally holding the bar in its unlocked position.

50 3. An automatic locking means for a trunk having three hinged together elements, comprising an escutcheon plate having a

shoulder, a lock plate having an elongated slot and a hook-like pivoted member provided with a wedging edge which engages the shoulder to draw two of the elements together and also having a recessed portion for lockingly engaging the shoulder, said hook-like member also having an elongated opening, a reciprocal bar engaged by the third element and having a projecting pin which extends through the elongated slot and the elongated opening, means for guiding the bar, and a spring means for normally holding the bar in its unlocked position. 65

4. An automatic locking means for a trunk having three hinged together elements, comprising an escutcheon plate having a shoulder, a lock plate having an elongated slot and a hook-like pivoted member provided with a wedging edge which engages the shoulder to draw the two parts together and also having a recessed portion for lockingly engaging the shoulder, said hook-like member also having an elongated opening, a reciprocal bar engaged by the third element and having a projecting pin which extends through the elongated slot and the elongated opening, said bar having a reduced lower end portion forming a shoulder, a coiled spring surrounding the reduced end portion and bearing against the shoulder, and a bracket member having a reduced upper end portion forming a shoulder which is engaged by the lower end of the coiled spring. 75

5. An automatic locking means for a trunk having three hinged together elements, comprising an escutcheon plate positioned on the outer side of one of the elements and having a shoulder, a hook-like pivoted member positioned on the outer side of one of the other elements and having a wedging edge which engages the shoulder to draw two of the elements together and also having a recessed portion for lockingly engaging the shoulder, a bar engaged by the third element only when said third element is moved towards locking position for moving the hook-like member to locking position, and means for normally holding the bar yieldingly in unlocked position. 95

In testimony whereof, I affix my signature.

FRANK H. LANGMUIR.
